51,686.

Specification for Design.

Patented Jan. 8, 1918.

Application filed September 14, 1915. Serial No. 50,711. Term of patent 14 years.

To all whom it may concern:

Be it known that I, HAROLD H. WILL, a citizen of the United States, residing at Syracuse, in the county of Onondaga and State of New York, have invented a new, original, and ornamental Design for a Candle-Lamp, of which the following is a specification, reference being had to the accompanying drawing, forming a part hereof.

In the drawings, Figures 1 and 2 are respectively, a plan and an elevation of a candle lamp of my design.

This design for a candle lamp comprises a discoidal base 1, a cylindrical cup 2 located centrally of the base and a chimney 3 rising from the cup; the base having a centrally depending portion or hub 4, a dished web portion 5 in the form of an inverted flattened cone, a roll or bead 6 at the peripheral edge of the base and a handle 7 at said peripheral edge; the cup 2 having the appearance of being an upward continuation of the hub 4 and terminating in a bead or lip 8 at its upper end; and the chimney be-

ing cylindrical in general form and tapering in rounding curves from a point above the center toward the upper end of the chimney.

The web or dished portion of the base is formed with a circular series or band of ornamental openings, and the cup is banded by a series of similar openings. The openings of the dished web portion in the cup are substantially H-shaped; and the chimney is formed with ornamentation consisting of lengthwise extending panels forked and interlocked at each end and annular bands in plain glass, while the remainder of the chimney is frosted.

I claim:

The ornamental design for a candle lamp, substantially as shown and described.

In testimony whereof, I have hereunto signed my name, at Syracuse, in the county of Onondaga, and State of New York, this 13th day of Sept., 1915.

HAROLD H. WILL.
